Attorney

UNITED STATES PATENT OFFICE.

CLARENCE F. BENJAMIN, OF MILFORD, CONNECTICUT.

HAIR CRIMPER.

Application filed February 14, 1925. Serial No. 9,083.

This invention relates to certain improvements in hair crimpers but more particularly has reference to that class of such devices in which there is a skeleton pivoted handle that is adapted to fold and engage over the ends of the crimping jaws so as to confine the hair.

The object of the invention is to produce a device of this character which shall grasp the hair firmly between a pair of spring actuated jaws, the spring element being furnished by the handle itself.

A further object of the invention is to so pivot the clamping jaws that there can be no sidewise movements such as would probably shear the hair.

Also the invention aims to produce a very simple and economical device of this description whose operation is quite facile.

20 In the accompanying drawings—

Figure 1 is an elevation of the improvement in its normal condition—

Figure 2 is a similar view showing the position of parts when the jaws are dis-

25 tended—

Figure 3 is an elevation of the device in its normal condition from a viewpoint at right angles to that which characterizes Figure 1, and

30 Figure 4 is an elevation of the device in folded condition.

Similar numerals of reference denote like parts in the several figures of the drawing.

35 1, 2, are the jaws having their rear ends terminating in diverging portions 3, 4, and 5 is a metallic band which encircles the jaws at their rear extremities at the point where the portions 3, 4, diverge, so that it will be clear that when these portions 3, 4, are 40 pinched together the jaws will open.

It will also be clear that with this manner of pivoting the jaws the latter are confined as against any sidewise movements.

45 The ends of the jaws are provided with notched portions 6 (only one being shown at Figure 3) which portions register when the jaws are closed.

7 is the handle which is made of spring wire having its terminals 8 hooked through the ends of the diverging portions 3, 4, so as to afford a very simple pivotal relation between the handle and these portions.

50 The connections between the handle and the portions 3, 4, are made against the resiliency of the spring of the wire that composes the handle, so that it will be clear that the

force of this spring always tends to keep the jaws in closed condition and in contact throughout the greater part of their length.

In the manipulation of my improvement, 60 the portions 3, 4, are pinched together to open the jaws, and a strand of hair is then placed between these jaws, whereupon the portions 3, 4, are released so as to cause the jaws to come together and clamp the hair; 65 the handle 7 is then grasped and turned so as to wind the strand of hair around the jaws 1, 2, and finally the handle 7 is folded so as to bring its end over the ends of the jaws and into engagement with the 70 notches 6 so as to lock this handle in this position, the ends of the jaws on both sides of the notches being rounded, as shown at Figure 3, in order that said ends may force the end of the handle outwardly and cause 75 the resilient action of the latter to automatically effect the locking engagement between said handle and notches.

It will thus be noted that no spring is employed except that which is furnished by the 80 handle itself, and that the grasp upon the hair is firm and that there is no danger of the jaws working sidewise, and therefore all grinding against the hair with a shearing effect is obviated.

85 While I prefer to employ the encircling band 5 as a means for holding the jaws together and permitting them to open and close nevertheless it will be clear that these jaws may be pivoted together by an ordinary rivet 90 passed through them, and therefore I do not wish to be limited in this respect.

Having thus described my invention what I claim is:—

95 A foldable hair crimper, comprising a pair of pivoted elongated separable jaws normally closed and in contact throughout the greater part of their length and having their heel ends diverging beyond the pivotal point, and a resilient bow-shaped wire handle 100 whose inner terminals are hooked under tension through the extremities of said diverging ends and thereby act to normally close said jaws, both of the outer ends of the latter having notches that align when the jaws are 105 closed and that are automatically engageable with the outer end of said handle when the jaws are closed and folded inwardly.

110 In testimony whereof I affix my signature hereto.

CLARENCE F. BENJAMIN.
